N°. 1,297 Fig. III.

Ornamental Design for

Parlor Stoves.

Walter W. Stanard

Fig. II.

Buffalo N.Y.
Patented July 31, 1860.

Fig. V.

Manufactured
by Walter W. Stanard
260 Broadway
New York City.

Fig. I.

Fig. IV.

Ass't to Jewell & Root - same place.

Walter W. Stanard

Des. 1297

Walter W. Stanard, of Buffalo, N.Y.
Assignor to
Sherman S. Jewett & Francis B. Root, of same place,
Letters Patent No. 1297, dated July 31, 1860,

~~~~~

The schedule referred to in these Letters Patent, and on making part of the same.

To all whom it may concern:

Be it known that I, Walter H. Standard, of the City of Buffalo, County of Erie, and State of New York, have invented or produced a new and original ornamental design for parlor stoves, and I do hereby declare that the following is a full, clear, and exact description thereof, reference being had to the accompanying photographic drawings, and the letters of reference marked thereon.

Fig. I. Represents the bottom plate of the stove. It is surrounded by a round and concave moulding, a, with oval embossed beads, b, at regular intervals in the concave and bead moulding, c, fillings between them. At the termination of the hearth, at either end of the plate, the moulding is formed into embossed leaves and scrolls, d, surrounding that portion of the plate which forms the bottom of the fire chamber, is a bead moulding, e, with concave denticulations at regular intervals.

Fig. II. Represents one of the side plates of the stove. It has a large embossed oval panel, f, with vertical concave flutings, f', and is surrounded by an oval ring of quarter round, and concave mouldings, g, terminating at each end in circular beads - and carved ornaments, h, and with adhering leaves, i, near the ends.

K, is a scalloped edge moulding with bead points, l, along the upper edge of the plate, and, m, are embossed fluted pillars with carved scroll ornaments, n, at the sides of the plate, o, are embossed scroll ornaments near either end of the ring. The opposite end plate is similar in all respects to the one just described.

Fig. III. Represents one of the end plates of the stove. It has a door, p, which is surrounded by a plain quarter round and bead moulding, q. It has an ovate embossed panel, r, with diamond-shaped reticulations and is surrounded by a plain half round moulding, s, terminating at the top in reversed scrolls, t, with adhering leaves, u; and at the bottom in a curved ornament v, and similar reversed adhering leaves u.

Along the upper edge of the plate is a scalloped edge moulding, x, with bead points similar to that at the upper edge of the side plate Fig. II.

The opposite end plate is the same as the one just described except that the door is a stationary panel.

Fig: IV. Represents the top plate of the stove. It has a scalloped edged border, w, with fluted points and ovate beads, x, with denticulated bases behind each point and a half round bead moulding, y, with embossed beads, z, at regular intervals.

Fig: V. Is the top plate of a sheet iron drum which sets upon the stove. It has a scalloped edged border formed of leaves, a', placed at regular intervals and connected by concave scroll mouldings, b', as represented.

Fig: VI. Represents the cover for the opening in plate Fig: V. It has central embossed shield, c', with diamond shaped reticulations, d', and radiating leaf pointed ornaments on the concave surface of the cover.

e', is an ornamental handle formed of scrolls, leaves and volutes, f.'

What I claim and desire to secure by letters patent, is, the ornamental design for a parlor stove herein described.
